(57) **CLAIM**

The ornamental design for a stackable watercraft floatation dock with rollers, as shown and described.

DESCRIPTION

FIG. 1 is a top perspective view of the stackable watercraft floatation dock with rollers of the present invention;

FIG. 2 is a bottom perspective view of the stackable watercraft floatation dock with rollers of FIG. 1;

FIG. 3 is a bottom plan view of the stackable watercraft floatation dock with rollers of FIG. 1;

FIG. 4 is a back end elevational view of the stackable watercraft floatation dock with rollers of FIG. 1;

FIG. 5 is a top plan view of the stackable watercraft floatation dock with rollers of FIG. 1;

FIG. 6 is a side elevational view of the stackable watercraft floatation dock with rollers of FIG. 1;

FIG. 7 is a front end elevational view of the stackable watercraft floatation dock with rollers of FIG. 1; and,

FIG. 8 is a top perspective view of the stackable watercraft floatation dock with rollers of FIG. 1 showing a watercraft and driver mounted thereon.

The broken lines are for illustrative purposes only and form no part of the claimed design.
